UNITED STATES PATENT OFFICE.

FRANK WAGNER AND WILLIAM L. WAGNER, OF CLEVELAND, OHIO.

DESIGN FOR A CANDELABRUM.

44,947.

Specification for Design.

Patented Nov. 25, 1913.

Application filed June 21, 1913. Serial No. 775,143. Term of patent 14 years.

To all whom it may concern:

Be it known that we, FRANK WAGNER and WILLIAM L. WAGNER, both citizens of the United States of America, residing at Cleveland, in the county of Cuyahoga and State of Ohio, have invented a new, original, and ornamental Design for Candelabra, of which the following is a specification, reference being had to the accompanying drawing, forming a part thereof.

The figure in the drawing illustrates an isometric view of the candelabrum showing the same when in position for use.

What we claim is:

The ornamental design for a candelabrum, as shown.

Signed at Cleveland, in the county of Cuyahoga and State of Ohio, this 17 day of June, 1913.

FRANK WAGNER.
WILLIAM L. WAGNER.
